US0D1054491S

(12) **United States Design Patent** (10) **Patent No.:** **US D1,054,491 S**
(45) **Date of Patent:** **** Dec. 17, 2024**

(54) **ORGANIZER**

(71) Applicant: **ShenZhen YiHong Technology Co., LTD**, ShenZhen (CN)

(72) Inventor: **Yi Dai**, ShenZhen (CN)

(73) Assignee: **ShenZhen YiHong Technology CO., LTD**, ShenZhen (CN)

(**) Term: **15 Years**

(21) Appl. No.: **29/927,266**

(22) Filed: **Feb. 2, 2024**

(51) LOC (14) Cl. **28-03**

(52) U.S. Cl.

USPC **D28/73**; D3/205; D19/78

(58) **Field of Classification Search**

USPC D19/76-90, 91, 92, 101-102, 103-107;
D28/73, 76, 77, 83; D3/205, 206;
D6/675.3

CPC A47B 57/30; A47B 96/067; A47B 63/00;
A47B 47/04; G09F 1/10; G09F 1/14

(57) **CLAIM**

The ornamental design for an organizer as shown and described.

DESCRIPTION

FIG. 1 is a first front and above perspective view of an organizer showing my new design;

FIG. 2 is a first back and bottom perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is an exploded view thereof;

FIG. 10 is another exploded view thereof;

FIG. 11 is a perspective view thereof, in an alternate configuration; and,

FIG. 12 is another perspective view thereof, in an alternate configuration.

The broken lines illustrate environmental elements of the organizer that form no part of the claimed design.

1 Claim, 9 Drawing Sheets
